Albert J. Dreitzer, New York, N. Y., assignor to
Pitman-Dreitzer & Co., Inc., New York, N. Y.,
a corporation of New York

Application October 28, 1949, Serial No. 5,760

Term of patent 14 years

(Cl. D36—2)

To all whom it may concern:

Be it known that I, Albert J. Dreitzer, a citizen of the United States of America and a resident of New York, in the county of New York and State of New York, have invented a new, original, and ornamental Design for a Combination Glass Coaster and Ash Tray or Similar Article, of which the following is the specification, reference being had to the accompanying drawing forming a part hereof:

Figure 1 is a top plan view of a combination glass coaster and ash tray or similar article, showing my new design.

Figure 2 is a side elevational view of the article shown in Figure 1.

Figure 3 is a sectional view taken along line 3—3 of Figure 1.

I claim:

The ornamental design for a combination glass coaster and ash tray or similar article, substantially as shown.

ALBERT J. DREITZER.
